UNITED STATES PATENT OFFICE

HENRY MARSH, OF CHICAGO, ILLINOIS, ASSIGNOR TO GRENNAN BAKERIES, INC., OF CHICAGO, ILLINOIS, A CORPORATION OF DELAWARE

DESIGN FOR A COOKY-DISPLAY CONTAINER

Application filed July 3, 1930. Serial No. 36,270. Term of patent 14 years.

To all whom it may concern:

Be it known that I, HENRY MARSH, a citizen of the United States, residing at Chicago, in the county of Cook and State of Illinois, have invented a new, original, and ornamental Design for a Cooky-Display Container, of which the following is a specification, reference being had to the accompanying drawing, forming part thereof.

The figure is a perspective view of the cooky display container embodying my design.

I claim:

The ornamental design for a cooky display container substantially as shown.

HENRY MARSH.
